UNITED STATES PATENT OFFICE.

JOSEPH KÖNIG, OF GAGGENAU, GERMANY.

FUMIGATOR.

SPECIFICATION forming part of Letters Patent No. 690,299, dated December 31, 1901.

Application filed September 5, 1901. Serial No. 74,437. (No model.)

To all whom it may concern:

Be it known that I, JOSEPH KÖNIG, watchmaker, a subject of the Grand Duke of Baden, residing at Gaggenau, in the Grand Duchy of Baden and German Empire, have invented certain new and useful Improvements in Fumigators, of which the following is a specification.

My invention relates to a fumigator or apparatus for producing smoke, and is particularly intended for use in preventing bees from attacking the operator during his work at the hives. A form of construction of this apparatus is represented in the accompanying drawings, in which—

Figure 1 is an elevation of the apparatus; Fig. 2, a vertical section; Fig. 3, a cross-section on the line A B, Fig. 1; and Fig. 4 is a detail view.

20 A clock or like spring *b*, driving a fan or blower *c*, is arranged in the sheet-metal casing *a*. The air is propelled by the fan *c* through a nozzle *d*, into the smoke-chamber *e*, provided near its lower part with a sieve-like bottom *f* and closed at the top with a sieve-like 25 detachable cover *g*, so that a part of the air passes through the bottom *f*, thus maintaining the burning of the tobacco or the like, which is placed on the sieve *f* in the chamber *h* and ignited. The other part of the air, driven upward by the fan *c*, passes through a pipe *i*, vertically and centrally arranged in the smoke-chamber, and draws along with it as it issues the smoke from the chamber *h*, 30 through the reticulate cover *g*, and thence through the pipe or nozzle *k*, so that the smoke escapes in the form of a strong jet through the nozzle *k*. The upper part of the casing *a* is provided with orifices *x*, so as to enable the air 35 entering through the same to cool the smoke-chamber *e*. A free space is provided for this purpose between the chamber *e* and the perforated upper part of the casing *a*.

The stopping-spindle *l* of the clockwork *b* 40 is provided with a lever *m* and with a wire *n*, to which latter a plate or flap *o* is attached for regulating or closing the air-supply opening to the blower *c*. The lever *m* serves also for arresting the clockwork, since a pin (not 45 shown in the drawings) mounted upon the shaft *l*, stops one of the wheels when the plate

o entirely closes the opening. (See Fig. 4 in dotted lines.)

The starting of the apparatus is effected as follows: The nozzle head or top *k* of the apparatus is turned back on its hinge or removed after turning down the wire-securing device *z*, the perforated cover *g* is then removed from the smoke-chamber *e*, a small piece of burning tinder or other igniter is then introduced and the tobacco or the like placed thereon, the cover *g* restored, and the top replaced. The springwork *b* is then wound up by means of the key *s* and the lever *m*, and thereby the plate *o* turned into the position 60 shown in full lines in Figs. 1 and 4, and the apparatus is ready for use.

Having now particularly described and ascertained the nature of my said invention and in what manner the same is to be performed, 70 I declare that what I claim is—

1. In a fumigator, a smoke-chamber having reticulated bottom and top, a pipe extending entirely through the smoke-chamber, and a fan and its casing below the smoke-chamber, 75 the fan-casing having a nozzle located below the said reticulated bottom and said pipe.

2. In a fumigator, a smoke-chamber having reticulated bottom and top, a pipe extending entirely through the smoke-chamber, a fan 80 and its casing, the fan-casing having a nozzle the delivery end of which is located below said reticulated bottom and pipe and said casing having an air-supply opening, and a manually-operable flap for regulating said air- 85 supply opening.

3. In a fumigator, a smoke-chamber having a reticulated bottom and a movable reticulated top whereby smoke-producing devices can be introduced into said chamber by lifting the top, a pipe passing through the smoke-chamber and means located below the smoke-chamber and said pipe for directing currents of air therethrough.

4. In a fumigator, a smoke-chamber having 95 a reticulated bottom a cover-piece hinged to said chamber having a piece of reticulated material constituting a top for said smoke-chamber, a draft-pipe in co-operative relation with the smoke-chamber, and means for sending currents of air simultaneously through the smoke-chamber and draft-pipe.

5. In a fumigator, a smoke-chamber having reticulated bottom and top, a pipe passing entirely through said smoke-chamber, a perforated jacket surrounding the smoke-chamber and separated therefrom by an air-space, and means for directing currents of air through the smoke-chamber and pipe from a place below the same.

In testimony whereof I have hereunto set my hand in presence of two subscribing witnesses.

JOSEPH KÖNIG.
